UNITED STATES PATENT OFFICE.

ROSE D. MURRAY, OF SEATTLE, WASHINGTON.

COVER FOR IRONING-BOARDS.

1,287,597.

Specification of Letters Patent. Patented Dec. 10, 1918.

Application filed December 12, 1917. Serial No. 206,844.

To all whom it may concern:

Be it known that I, ROSE D. MURRAY, citizen of the United States, residing at Seattle, in the county of King and State of Washington, have invented a certain new and useful Improvement in Covers for Ironing-Boards, of which the following is a specification.

My invention relates to removable covers for ironing boards, and the object of my invention is to provide an ironing board cover which shall include two separable portions one of which portions comprises a pad of soft yielding material formed to adapt it to extend throughout the length and breadth of the top surface of an ironing board and provided with means for releasably fastening it in its operative position on said ironing board, and the other of which portions consists in a jacket of tough smooth textile fabric formed to adapt it to be disposed to inclose the edge portions of said ironing board and the top surface of the associated pad in such manner as will completely press the soft yielding material of said pad and confine it in the form of a flat even surface that cannot be ruffled by the act of ironing on said ironing board.

I accomplish this object by devices in the accompanying drawings, wherein—

Figure 1 is a view in side elevation of an ironing board cover embodying my invention as it will appear when disposed on an ironing board ready to be fastened thereto;

Fig. 2 is an enlarged view of the same in cross-section on broken line 2, 2, of Fig. 1;

Fig. 3 is a view of the same in elevation of its rounded end portion;

Fig. 4 is a plan view of a detail of the same; and

Fig. 5 is a plan view of another detail of the same.

Referring to the drawings, throughout which like reference numerals designate like parts, 6 is a common form of ironing board which is shown in cross-section in Fig. 2 and indicated by dotted lines in Fig. 1.

Disposed on the top surface of the ironing board 6 is a pad 7 of soft yielding material, as cotton batting, disposed between two pieces of cotton cloth, which pad 7 in shape of outline and in dimensions is like the top surface of the ironing board 6.

As shown more clearly in Fig. 4, attached to both of the side edge portions of the pad

7 at opposite points thereof respectively are tape-like strings 9, 10, 11, 12, 13 and 14 whose full lengths are not indicated in the drawing, but whose lengths are sufficient to 60 adapt opposite ones of them to be tightly drawn together beneath the ironing board 6 and there tied in a knot thus to fasten said pad 7 on the ironing board 6.

Attached to the end edge portion of the wider end of the pad 7 is a loop 15 of tape which is of a length to adapt it to extend beneath the end portion of the ironing board 6 to a point registering with the strings 9 and 10 so that one or both of said strings 9 70 and 10 may be passed through said loop 15 before said strings 9 and 10 are tied together thus to cause loop 15 to prevent the pad 7 from moving toward the opposite end of the ironing board in response to the operation 75 of ironing clothes thereon, a movement of said pad 7 in the opposite direction being prevented by tying the strings 13 and 14 at tapered narrow end portion of said ironing board 6.

Thus the pad 7 may be secured against endwise and sidewise movements on the ironing board 6 while its top surface may be ruffled and uneven.

In order to smooth and flatten the top surface of the pad 7 and to bind its soft yielding material more firmly to the surface of the ironing board I have provided a jacket 16 made of tough, smooth textile fabric and of a form corresponding in contour to the 90 contour of the ironing board 6 but of larger area, which jacket 16 is thus adapted to inclose the top surface of the pad 7 and all the edge portions of the ironing board 6.

Attached to the hemmed side edges of the 95 jacket 16 at opposite points thereof are a plurality of tape strings 17 and 18, 19 and 20, 21 and 22, 23 and 24, 25 and 26, as shown in Fig. 5, which strings are to be of sufficient length to adapt them to be tied together beneath the ironing board 6.

The edge portion of the rounded end of the jacket 16 is folded over to form a wide hem 27 between the folds of which extends a puckering string 28.

Attached to the edge portion of the wider end of the jacket 16 is a loop of tape 29.

The jacket 16 is symmetrically disposed on the top of the pad 7 so that all of its edge portions extend downwardly lower than the 110 bottom of the ironing board 6 and thereupon one or both of the strings 17 and 18 are pro-

jected through the loop 29 and said strings 17 and 18 are then pulled together and tightly tied, then the opposite end portions of the puckering string 28 are drawn together with force beneath the ironing board 6 and there tied, thus coacting with the loop 29 to stretch the cloth of the jacket 16 in an endwise direction, and thereupon the strings 19 and 20, 21 and 22, 23 and 24 and 25 and 10 26 are respectively drawn together with force and tied beneath the ironing board 6, thus to stretch the cloth of the jacket 16 in side-wise directions and cause it to compress, flatten and confine the material of the pad 7, 15 and to present a smooth flat surface upon which clothes may be ironed in an obvious manner.

Obviously the shape of the outline of the pad 7 and the jacket 16 may be changed to 20 correspond to ironing boards of different shapes, and the number of binding strings that are attached to the edge portions of the pad 7 and the jacket 16 may be changed without departing from the spirit of my in- 25 vention.

What I claim is:

1. A cover for an ironing board including a covering member substantially conforming to the form of the board and having 30 a loop attached to the edge of one end thereof, a plurality of oppositely arranged laterally extending binding strings attached to the side edge portions of said covering member, one pair of said binding strings being adapted to be fastened to the edge of the wider end thereof, and a plurality of oppositely arranged laterally extending binding strings attached to the side 35 edge portions of said covering member, one pair of said binding strings being adapted to be fastened under the board at the reduced end thereof to prevent longitudinal movement of the covering member relative to the board in one direction, and means at the other end 40 of said covering member to prevent longitudinal movement of the covering member relative to the board in the opposite direction.

2. A cover for an ironing board including a covering member substantially conforming 45 to the form of the board and having a loop attached to the edge of one end thereof, a plurality of oppositely arranged laterally extending binding strings attached to the side edge portions of said covering member, one 50 pair of said binding strings being adapted to extend through said loop and then be fastened under the board at one end to prevent longitudinal movement of the covering member relative to the board in one direction, and means at the other end portion of said covering member to prevent longitudinal movement of the covering member relative to the board in the opposite direction, said means including a wide hem formed on said other 60 end of the covering member and having a puckering string extending through the folds thereof.

3. A cover for an ironing board having a reduced end portion, including a covering 65 member substantially conforming to the form of the board and having a loop attached to the edge of the wider end thereof, and a plurality of oppositely arranged laterally extending binding strings attached to the side 70 edge portions of said covering member, one pair of said binding strings being adapted to be fastened under the board at the reduced end thereof to prevent longitudinal movement of the covering member relative to the 75 board in one direction, and another pair of said binding strings being adapted to extend through said loop at the wider end of the board and then be fastened under the latter to prevent longitudinal movement of the 80 covering member relative to the board in the opposite direction.

In witness whereof, I hereunto subscribe my name this 6th day of December A. D.; 1917.

ROSE D. MURRAY.
